UNITED STATES PATENT OFFICE.

FREDERICH J. FEINTHEL AND JOHN G. DINKELEBIHLER, OF CINCINNATI,
OHIO.

MAIL-BAG.

SPECIFICATION forming part of Letters Patent No. 329,155, dated October 27, 1885.

Application filed August 17, 1885. Serial No. 174,661. (No model.)

To all whom it may concern:

Be it known that we, FREDERICH J. FEINTHEL and JOHN G. DINKELEBIHLER, citizens of the United States, residing at Cincinnati, 5 in the county of Hamilton and State of Ohio, have invented certain new and useful Improvements in Mail-Bags, of which the following is a specification, reference being had therein to the accompanying drawings.

10 The first part of our invention comprises a novel combination of outer and inner flaps, buttons, and slotted plates, wherewith the mouth of a mail-bag can be securely closed and yet be readily opened after a padlock has 15 been disengaged from an appropriate staple, the details of this combination being herein-after more fully described.

15 The second part of our invention consists in combining with a mail-bag a peculiar form of keeper or holder that secures the bag-label in place, as hereinafter more fully described.

20 The third part of our invention comprises a novel combination of devices for attaching this holder to the bag, as hereinafter more 25 fully described.

25 In the annexed drawings, Figure 1 is a front elevation showing our improved mail-bag closed and the outer flap secured with a padlock. Fig. 2 is a similar elevation, but showing said flap unlocked and thrown open. Fig. 3 shows the bag after the inner flap has been released and opened. Fig. 4 is an enlarged vertical section of the upper part of the bag, taken at the line Y Y of Fig. 2. Fig. 5 is a horizontal section of the bag taken at the line 30 Z Z of Fig. 2. Fig. 6 is an enlarged longitudinal section of the label holder or keeper. Fig. 7 is a vertical section of said label-holder.

35 A represents the front, and B the back, of 40 a mail-bag of any suitable size and material, said back having secured to it by rivets b the main or outer flap, C, near the free edge of which latter is attached a plate, D, having a slot, d, to receive a staple, E, wherewith is engaged a padlock, G. Furthermore, this outer 45 flap, C, has secured to it a label holder or keeper, N, the details of which will be described hereinafter.

50 The back B is prolonged a sufficient distance above the front A to afford an inner or secondary flap, H, to which is fastened a plate,

I, slotted at i to admit the staple E, previously alluded to. In addition to this plate I, said flap H has secured to it a pair of plates, J J', each of the latter being furnished with an eye, j, and slot j', which eyes and slots are adapted to receive headed pins or buttons K K', projecting forwardly from plates k k'. These plates k k' are attached to a re-enforce or band, L, riveted to the upper portion or mouth of 60 the bag, said band being further provided with a plate, e, from which projects the staple E.

M is a handle that may be attached to the rear of the outer flap, C, as seen in Fig. 4; or a handle may be fastened on each side of the 65 bag, one of which side handles is seen at M' in Fig. 2.

70 Our label-holder consists of a case, N, open at one end but closed at the other end, and provided with an upper flange, n, and lower flange, n', as seen in Fig. 7. Projecting from the open end of this case is a spring, O, terminating with a shoulder or other stop, o, capable of retaining within said case a thin strip or plate, P, upon whose exposed face the destination of the mail-bag is either written or otherwise inscribed. Projecting rearwardly from said case are loops or staples R R', which, after passing through suitable holes cut either in the bag or flap C, are traversed by a wire, 80 S, as more clearly seen in Fig. 6.

85 When our mail-bag is closed, the inner flap, H, is turned down in front and the slot i of plate I is engaged over the staple E, while the shanks of buttons K K' occupy the slots j' j' of plates J J', as seen in Fig. 2. The outer flap, C, is then turned down over the inner flap, H, as seen in Fig. 1, thereby concealing the plates I J J' and buttons K K'. When thus turned down, the staple E passes through 90 the slotted plate D d of said outer flap, and the padlock G being now engaged with said staple, the bag is securely fastened. The label-strip P is then inserted in the holder N, and is retained in place by the shoulder o of spring 95 O snapping over the exposed end of said strip.

When the bag arrives at its destination, the padlock G is disengaged from the staple E and the outer flap, C, is thrown open, thereby exposing the inner flap, H, as seen in Fig. 2. 100 The lower portion of this flap H is then disengaged from said staple, and said flap is shoved

up, so as to cause the shanks of buttons K K' to traverse the slots j' j' of plates J J'. As soon as these buttons enter the eyes j j of said plates the flap H is free, and is at once 5 thrown open, thereby exposing the mouth T of the bag, as seen in Fig. 3.

If it should be desired to detach the label-holder, the act can be readily accomplished by simply pulling the rod S out of the loops 10 R R' of the case N.

The label-strip P can be as readily slipped out of the case after the spring O has been forced back far enough to allow the outer end of said strip to clear the shoulder or other 15 dent, o, of said spring.

Finally, this case N can either be integral with the plate D, as seen in Fig. 1, or it may be detachably coupled to the bag in the manner shown in Figs. 2, 6, and 7.

20 We claim as our invention—

1. The mail-bag A B, having its mouth closed by an outer flap, C, and inner flap, H, the front A of said bag being provided with a staple-plate, E e, and button-plates K k K' k', 25 which buttons K K' engage with the slotted

and eyed plates J j j' J' j j' of inner flap, H, and the staple E passes through the slotted plates I i and D d of said inner and outer flaps, for the purpose specified.

2. The combination, with a mail-bag, of the 30 flanged label-holder N n n', provided with detachable attaching devices, substantially as shown and described, open at one end, but closed at the other end, said open end being provided with a spring, O, whose shoulder o 35 bears against the label-strip P in the manner herein described, and for the purpose stated.

3. The combination, in a mail-bag, of the label-holder N, having staples R R' on its back, which staples pass through suitable holes in 40 the bag or flap and are traversed by the rod S, for the purpose herein described.

In testimony whereof we affix our signatures in presence of two witnesses.

FREDERICH J. FEINTHEL.
JOHN G. DINKELBIHLER.

Witnesses:

JAMES H. LAYMAN,
SAM'L. S. CARPENTER.
